PROCESS FOR RECOVERING TOLUENE FROM
HYDROCARBON MIXTURESCharles R. Clark, Springfield Township, Mont-
gomery County, Pa., assignor to Allied Chemical
& Dye Corporation, New York, N. Y., a corpora-
tion of New York

Application November 26, 1943, Serial No. 511,832

13 Claims. (Cl. 202—42)

This invention relates to the recovery of toluene from hydrocarbon mixtures.

This application is a continuation in part of my copending applications Serial Nos. 368,664 and 368,665, both filed December 5, 1940.

Toluene occurs in various proportions in many natural and synthetic hydrocarbon mixtures. Petroleum distillates of the gasoline type may contain considerable proportions of toluene. Light oils produced by the gasification of coal contain relatively large proportions of toluene. Also synthetic hydrocarbon mixtures produced by various catalytic processes may contain toluene in substantial quantities.

Complex hydrocarbon oil mixtures comprising non-aromatic hydrocarbons such as paraffins, olefins and naphthalenes and containing aromatic compounds, including toluene, may be treated by well-known selective solvents to produce fractions relatively rich in the aromatic compounds. For example, suitable petroleum distillate fractions containing toluene and other aromatic compounds may be extracted with sulfur dioxide to yield fractions containing relatively greater proportions of aromatic compounds, including toluene. In such cases toluene is associated with non-aromatic oils which may be olefinic, paraffinic, or naphthenic in character. A considerable proportion of these oils cannot be completely separated from the toluene by direct fractionation because of the proximity of their boiling points to that of toluene or because of their ability to form constant boiling mixtures with toluene. In some cases toluene produced by the gasification of coal or by various catalytic processes may be associated with difficultly separable oils of the same general character.

By fractional distillation of the above types of complex hydrocarbon mixtures fractions relatively high in toluene content may be obtained. These toluene fractions, however, will still contain large proportions of the non-aromatic constituents whose boiling points at any given pressure are in the neighborhood of the boiling point of toluene at the same pressure, or which form with toluene or other constituents of the mixture azeotropes distilling in the range of temperatures at which toluene distills from the mixture. In the specification and claims, I refer to such difficultly separable constituents which distill over the same temperature range as the toluene and from which the toluene is not separable by a conventional distillation as "like-boiling" constituents, oils, etc.

For many purposes to which toluene is put, it

is desirable to use as pure a material as is economically available. For example, toluene is largely used for the production of TNT, for which purpose a so-called "nitration grade" of toluene, which is toluene of relatively high purity, is employed. Conventional fractional distillation will not separate toluene of sufficiently high purity for such purposes from complex mixtures of the type described above, e. g., oils of petroleum origin.

A process has been developed whereby toluene of relatively high purity may be recovered from complex hydrocarbon oil mixtures comprising toluene and non-aromatic hydrocarbons from which the toluene is not separable by a conventional distillation. The process involves a distillation of the complex mixtures with a compound (hereinafter designated an azeotropic agent) which forms minimum-boiling azeotropes with the like-boiling non-aromatic hydrocarbons of such mixtures, which azeotropes distill from the complex mixtures at lower temperatures than the corresponding azeotrope of toluene.

An important factor in the efficient separation of like-boiling non-aromatic constituents from toluene fractions by azeotropic distillation is the provision of an azeotropic agent which forms with the like-boiling non-aromatic hydrocarbon azeotropes having, under the distillation conditions prevailing, vapor pressures sufficiently different from those of toluene and of any toluene azeotrope present at the distillation temperature to permit sharp separation of toluene without excessive rectification.

A second important factor in the economical separation of like-boiling non-aromatic hydrocarbons from toluene fractions is the provision of an azeotropic agent which has a high capacity for carrying off as distillate the like-boiling non-aromatic hydrocarbons; i. e., a compound which with like-boiling non-aromatic hydrocarbons form azeotropes comprising a high ratio of hydrocarbons to azeotropic agent. While certain azeotropic agents may effectively separate like-boiling non-aromatic hydrocarbons from toluene fractions the oil:agent ratio is so low that large quantities of the agent must be distilled in proportion to the quantity of toluene fraction being treated; accordingly, apparatus of great size and exorbitant cost must be employed, excessive heat losses are incurred and substantial distillation losses in the tail gases are incurred.

It is an object of this invention to provide a process for the recovery of toluene from mixtures of toluene and non-aromatic hydrocarbons from

which the toluene cannot be separated by a conventional distillation, which process is capable of producing a toluene of high purity and is particularly economical with respect to the proportion of azeotropic agent necessary.

In accordance with the present invention, a toluene oil containing like-boiling non-aromatic hydrocarbons not separable from the toluene by conventional distillation is fractionally distilled with a nitroparaffin boiling within the range of 110° to 125° C., with 2-nitropropane (boiling at about 120° C.) or nitroethane (boiling at about 115° C.). These nitroparaffins form with the like-boiling non-aromatic hydrocarbons of such oils, azeotropes which distill from the resulting mixtures at temperatures substantially below those at which toluene in substantial quantities distill. Moreover, the azeotropes of these nitroparaffins with such like-boiling non-aromatic hydrocarbons contain a particularly low ratio of nitroparaffins to the like-boiling non-aromatic hydrocarbons, and this property is an important feature in the effectiveness of the separation process of the present invention.

Use of nitroethane and 2-nitropropane as azeotropic agents for toluene recovery is disclosed in my applications, Serial Nos. 368,664 and 368,665, respectively, of which this application is a continuation-in-part.

In the application of the invention to the recovery of toluene from oils of moderate boiling range but in which the toluene concentration is low, or from oils of wide boiling range, it is preferred to fractionally distill the oil in conventional manner to provide an enriched toluene fraction of relatively limited boiling range. Although many toluene fractions having end boiling points substantially above the boiling point of toluene, for example, having end boiling points up to about 118° C., may be azeotropically distilled in accordance with the teachings of this invention, the process of the invention is preferably applied to toluene fractions having end points substantially corresponding to the boiling point of toluene, e. g., fractions having end points of about 111° C.

The process of the invention is preferably applied to toluene fractions so cut as to exclude forerunnings which do not contain substantial proportions of toluene. For example, the invention is applied to toluene fractions which preferably do not contain substantial proportions of oils normally distilling below 95° C. or more preferably are free from substantial proportions of oils normally distilling below 100° C.

The term "toluene fraction" is used herein to designate any oil fraction containing both toluene and other hydrocarbons which, under the conditions maintained in direct distillation processes as commonly used for distilling oils, distill from the oil fraction within the same temperature range as the toluene.

By distillation of toluene fractions in the presence of nitroparaffins boiling below 125° C. in accordance with the present invention, very effective fractionation is obtainable. From 90% to 99% or more of the like-boiling non-aromatic hydrocarbons may be removed from mixtures thereof with toluene by this process and high yields of toluene of 95% or higher, e. g., 99%-100% purity are obtained.

Considerable latitude is permissible in the choice of suitable proportions of nitroparaffin to be used in carrying out the present process. Substantial excesses of the nitroparaffins may be used

and the excess may be retained in the distillation residue. In general, the amount of the nitroparaffin should be sufficient to maintain the distillation temperature not higher than the boiling point of the toluene-nitroparaffin azeotrope at distillation pressure. A rise of temperature above this control temperature indicates a deficiency of nitroparaffin, as may also an abrupt rise below this value. Should the quantity of azeotropic agent be deficient, additional quantities should be added to overcome the deficiency. Sufficient 2-nitropropane to maintain a vapor concentration thereof at overhead temperatures between the boiling point of the toluene-nitroparaffin azeotrope at the prevailing pressure and about 20 centigrade degrees therebelow, equivalent to 1 part by volume of liquid nitroparaffin for each 3 parts by volume of oil condensate, has been found to be adequate for the production of a highly refined toluene. The proportion of nitroethane may advantageously be somewhat greater, e. g., sufficient to maintain a vapor concentration of nitroethane equivalent to between 1 and 2 parts by volume of liquid nitroethane for each 2 parts by volume of oil condensate. For example, between 3 and 8 volumes of 2-nitropropane for each 10 volumes of non-aromatic hydrocarbons in the toluene fraction and from between 1 and 2 volumes of nitroethane for each 2 volumes of the non-aromatic hydrocarbons is ordinarily sufficient to effect good separation.

The process of the present invention may be conducted at atmospheric pressure or at pressures higher or lower than atmospheric. Since the results are highly satisfactory at ordinary pressures, there is normally no occasion for deviation from such pressures insofar as the separation itself is concerned. Lower than atmospheric pressures may improve the steam consumption, but this advantage must be balanced against higher equipment cost. It will be appreciated that in the event higher or lower than atmospheric pressures are employed, the temperatures of distillation should be raised or lowered correspondingly.

While the invention contemplates the production of toluene products of any desired purity, it is preferred to provide sufficient nitroparaffin and to control the distillation so as to yield a toluene product containing at least a 9:1 weight ratio of toluene to like-boiling non-aromatic hydrocarbons, and more preferably to recover toluene of 95% to substantially 100% purity.

55 In practicing the invention, it is preferred to start with a toluene fraction at least 90% by weight of which distills at vapor temperatures between about 100° and 111° C. at atmospheric pressure, said fraction containing between 50% and 90% by weight of toluene. The toluene may be recovered from such fractions in accordance with the present invention by distilling it in the presence of 2-nitropropane or nitroethane in the proportions hereinabove disclosed.

65 While it is preferred that the toluene fractions treated in accordance with the invention contain only small quantities, if any, of hydrocarbons distilling from the fractions at temperatures above that at which toluene distills off therefrom, the presence of such higher-boiling hydrocarbons is not excluded. Such hydrocarbons may be left with the toluene product at the conclusion of the distillation process of the invention and thereafter the toluene may be separated from them 70 by conventional fractional distillation. This may

be accomplished in separate apparatus or in a lower section of the same column if a continuous column is employed, or in the same still if a batch still is employed.

The process of the invention may be conducted in conventional distillation equipment, preferably equipment capable of effecting a relatively sharp fractionation. Thus, for batch operations a simple boiler provided with a rectifying column may be employed and for continuous operations a column still may be employed. The accompanying drawing illustrates diagrammatically an arrangement of conventional equipment which may be employed for carrying out the invention.

The following examples illustrate the application of the invention to typical complex hydrocarbon mixtures of the type discussed above.

Example 1.—A complex mixture of petroleum origin having, when fractionally distilled at atmospheric pressure, a vapor temperature range of 107.5° C. to 110.5° C. and comprising 67% by volume of toluene and the remainder essentially paraffinic, olefinic and naphthenic hydrocarbon oils which are not separable from the toluene by conventional distillation, is mixed with an equal volume of 2-nitropropane. The mixture is charged to a conventional still provided with a rectifying column (the equivalent of 18 theoretical plates) and distilled with return of part of the condensate as reflux (20:1 reflux ratio). The distillation begins at a temperature around 96° C. and the temperature gradually rises to about 108° C. which is about 1½-2 centigrade degrees below the boiling point of the 2-nitropropane-toluene azeotrope (approximate B. P. 110° C. at 760 mm. of mercury, absolute pressure). At this point in the distillation there remains as residue a toluene product comprising about 86% toluene corresponding to about 90% of the toluene in the original complex mixture. By carrying the oil distillation further, i. e., to approximately the 50% point (50% of the oil over as distillate), a residual toluene product of better than 92% purity representing three-fourths or more of the toluene initially present in the complex mixture is produced. If the distillation is carried to the 60% point, about two-thirds of the total toluene content of the complex mixture is recovered as a 95% toluene product. By continuing to the 80% point, about one-third of the total toluene content of the complex mixture is recovered as a substantially 100% toluene product.

In each of the above three instances, the toluene product recovered is associated with 2-nitropropane from which it may be separated by washing with dilute NaOH solution. The nitropropane may be recovered from the washing agent by acidification of the washings. 2-nitropropane associated with distillate may be separated from the oils in a similar manner.

In conducting the process as a batch distillation with only a moderately effective rectifier, intermediate distillate containing both toluene and non-aromatic oils in substantial quantities may be separated as a second distillate cut and returned to the still with a new batch of complex hydrocarbon mixture. For example, the distillation may be carried to a point at which 40% of the oil has distilled over and this distillate, which is relatively low in toluene, may be collected as the first cut. The distillation then may be continued until 60% of the mixture has distilled over and this 40% to 60% fraction may be returned with the next charge. The 60% to 100%

distillate, or residue, if it is not desired to effect distillation of the toluene, may be recovered as the toluene product. This procedure produces a toluene product of good purity without sacrifice of yield, giving, for example, from a 67% toluene mixture a 90% yield and 95% or higher purity.

Example 2.—A complex mixture of petroleum origin having, when fractionally distilled at atmospheric pressure, a vapor temperature range of 107.5° C. to 110.5° C. and comprising 67% by volume of toluene and the remainder essentially paraffinic, olefinic and naphthenic hydrocarbon oils which are not separable from the toluene by conventional distillation, is mixed with an equal volume of nitroethane. The mixture is charged to a conventional still provided with a rectifying column (the equivalent of 18 theoretical plates) and distilled with return of part of the condensate as reflux (20:1 reflux ratio). The distillation begins at a temperature around 82° C. and the overhead temperature gradually rises to about 104° C., which is about 2 degrees below the boiling point of the toluene-nitroethane azeotrope (approximate B. P. 106° C. at 760 mm. of mercury, absolute pressure). During this period of the distillation, nitroethane and most of the non-aromatic hydrocarbon oils distill off. Depending upon the effectiveness of rectification varying small proportions of toluene may also distill off. Residue in the still comprises more than 90% of the toluene in the original complex mixture and from 4% to 6% of non-aromatic oils; that is, the residue, is 94% to 96% pure toluene except for nitroethane which may be removed by washing with dilute NaOH solution. The nitroethane may be recovered from the washing agent by acidification of the washings.

Toluene of greater purity may be obtained by carrying the distillation to a slightly higher overhead temperature. Thus, by carrying the overhead temperature to about 106° C., a toluene product of better than 97% purity is obtained. Further, by separately collecting the portion of the distillate which comes over after the first 20% of the oil has been distilled off and before 50% of the oil is distilled off and adding this portion to a subsequent still charge, the yield of toluene may be substantially increased, e. g., 95% yield of toluene of 98% to 99% purity may be obtained from a 67% toluene fraction.

In general, the process of the present invention is effective to produce toluene yields of 70% or 80% to 90% or more, with 80% to 99+ % of the like-boiling non-aromatic hydrocarbons removed from toluene fractions of 50% to 90% toluene content without the use of more than customarily efficient rectifiers.

In the claims, the temperatures specified for the boiling points are determined at atmospheric pressure (760 mm. of mercury). It will be understood that the reference in the claims to a hydrocarbon mixture boiling within the range of 95° to 118° C. is not intended to restrict the claims to such mixture, all of which boils within said range, but is intended to include hydrocarbon mixtures containing appreciable but small (say of the order of 20% by volume) amounts of lower boiling constituents and preferably little or no constituents boiling above 118° C.

By treatment of toluene products of the present process with sulfuric acid and fractionally distilling to separate reaction products, the highest nitration grade of toluene is obtainable.

I claim:

1. A process for the recovery of toluene from a complex hydrocarbon mixture containing toluene and non-aromatic hydrocarbons not separable from the toluene by conventional distillation of the hydrocarbon mixture, which process comprises fractionally distilling the hydrocarbon mixture with a sufficient amount of a nitroparaffin boiling within the range of 110° to 125° C. to vaporize and remove as distillate a substantial proportion of said non-aromatic hydrocarbons.

2. The method of recovering toluene from a complex hydrocarbon mixture containing toluene and non-aromatic hydrocarbons not separable from the toluene by conventional distillation of the hydrocarbon mixture, which method comprises fractionally distilling the hydrocarbon mixture with sufficient nitroethane to vaporize and selectively remove as distillate at least a substantial proportion of said non-aromatic hydrocarbons.

3. The method of recovering toluene from a complex hydrocarbon mixture containing toluene and like-boiling non-aromatic hydrocarbon oils, which method comprises segregating a toluene oil fraction boiling substantially within the range of 95° C. to 118° C., whereof at least 90% by weight normally distills at vapor temperatures between 100° C. and 111° C. and whereof between 50% and 90% by weight consists of toluene, mixing said toluene oil fraction with between 1 and 2 volumes of nitroethane for each 2 volumes of non-aromatic hydrocarbons in said toluene oil fraction, fractionally distilling the nitroethane-oil mixture, and separating, as at least one fraction of low aromatic content, a distillate going off at overhead temperatures below the boiling point of the toluene-nitroethane azeotrope at the prevailing pressure, thereby leaving behind a product enriched in toluene, the hydrocarbon content of said product being at least 95% toluene.

4. The method of recovering toluene from a complex hydrocarbon mixture containing toluene and like-boiling non-aromatic hydrocarbon oils, which method comprises segregating a toluene oil fraction boiling substantially within the range of 95° C. to 118° C., whereof at least 90% by weight normally distills at vapor temperatures between 100° C. and 111° C. and more than 50% but less than 90% by weight consists of toluene and the balance consists for the most part of like-boiling hydrocarbons, mixing said toluene oil fraction with between 1 and 2 volumes of nitroethane for each 2 volumes of non-aromatic hydrocarbons in said toluene oil fraction, fractionally distilling the nitroethane-oil mixture, and separating, as at least one fraction of low aromatic content, a distillate going off at overhead temperatures below the boiling point of the toluene-nitroethane azeotrope at the prevailing pressure, and recovering as residue from such distillation a toluene product containing at least 80% of the toluene and less than 20% of the like-boiling non-aromatic hydrocarbon oils initially present in said toluene oil fraction, the hydrocarbon content of said product being at least 95% toluene.

5. A process for the recovery of substantially pure toluene from a complex hydrocarbon mixture, whereof at least 90% by weight normally distills at vapor temperatures between 100° C. and 111° C., said mixture containing toluene and paraffinic hydrocarbons not separable from the toluene by conventional distillation of the mixture, which comprises fractionally azeotropically dis-

tilling the mixture with sufficient nitroethane to vaporize and selectively remove as distillate substantially all of the hydrocarbons except toluene present in said mixture, thereby leaving behind a product enriched in toluene, the hydrocarbon content of said product being at least 95% toluene.

6. A process for the recovery of substantially pure toluene from a complex hydrocarbon mixture containing toluene and like-boiling non-aromatic hydrocarbons, which comprises distilling the mixture through a fractionating column in the presence of nitroethane, maintaining in the fractionating column a sufficient concentration of nitroethane so that the overhead vapor temperature is not above the boiling point of the toluene-nitroethane azeotrope at the prevailing pressure, and conducting the distillation under these conditions until a residue is produced in which the ratio by weight of toluene to like-boiling non-aromatic hydrocarbons is at least 95:5.

7. The method of recovering toluene from a complex hydrocarbon mixture containing toluene and like-boiling paraffinic hydrocarbons, said mixture being substantially free from hydrocarbons normally boiling above 118° C., which comprises fractionally distilling said mixture in the presence of sufficient nitroethane to vaporize and selectively remove as distillate substantially all of said like-boiling paraffinic hydrocarbons, thereby leaving behind a product enriched in toluene, the hydrocarbon content of said product being at least 95% toluene.

8. The process for the recovery of toluene from a complex hydrocarbon mixture containing toluene and non-aromatic hydrocarbons not separable from the toluene by conventional distillation of the hydrocarbon mixture, which process comprises fractionally distilling the hydrocarbon mixture with sufficient 2-nitropropane to vaporize and remove as distillate at least a substantial proportion of said non-aromatic hydrocarbons.

9. The process for the recovery of toluene from a complex hydrocarbon mixture containing toluene and like-boiling non-aromatic hydrocarbon oils, which process comprises segregating a toluene oil fraction boiling substantially within the range of 95° C. to 118° C., whereof at least 90% by weight normally distills at vapor temperatures between 100° C. and 111° C. and whereof between 50% and 90% by weight consists of toluene, mixing said toluene oil fraction with between 3 and 8 volumes of 2-nitropropane for each 10 volumes of non-aromatic hydrocarbons in said toluene oil fraction, fractionally distilling the 2-nitropropane-oil mixture, and separating, as at least one fraction of low aromatic content, a distillate going off at overhead temperatures below the boiling point of the toluene 2-nitropropane azeotrope at the prevailing pressure, thereby leaving behind a product enriched in toluene, the hydrocarbon content of said product being at least 95% toluene.

10. The process for the recovery of toluene from a complex hydrocarbon mixture containing toluene and like-boiling non-aromatic hydrocarbon oils, which process comprises segregating a toluene oil fraction boiling substantially within the range of 95° C. to 118° C., whereof at least 90% by weight normally distills at vapor temperature between 100° C. and 111° C. and more than 50% but less than 90% by weight consists of toluene and the balance consists for the most part of like-boiling hydrocarbons, mixing said toluene oil fraction with between 3 and 8 volumes

of 2-nitropropane for each 10 volumes of non-aromatic hydrocarbons in said toluene oil fraction, fractionally distilling the 2-nitropropane-oil mixture, and separating as at least one fraction of low aromatic content, a distillate going off at overhead temperatures below the boiling point of the toluene 2-nitropropane azeotrope at the prevailing pressure, and recovering as residue from such distillation a toluene product containing at least 70% of the toluene and less than 20% of the like-boiling non-aromatic hydrocarbon oils initially present in said toluene oil fraction, the hydrocarbon content of said product being at least 95% toluene.

11. A process for the recovery of substantially pure toluene from a complex hydrocarbon mixture, whereof at least 90% by weight normally distills at vapor temperatures between 100° C. and 111° C., said mixture containing toluene and paraffinic hydrocarbons not separable from the toluene by conventional distillation of the mixture, which comprises fractionally azeotropically distilling the mixture with sufficient 2-nitropropane to vaporize and selectively remove as distillate substantially all of the hydrocarbons except toluene present in said mixture, thereby leaving behind a product enriched in toluene, the hydrocarbon content of said product being at least 95% toluene.

12. A process for the recovery of substantially pure toluene from a complex hydrocarbon mixture containing toluene and like-boiling non-aromatic hydrocarbons, which comprises distilling the mixture through a fractionating column in the presence of 2-nitropropane, maintaining in the fractionating column a sufficient concentration of 2-nitropropane so that the overhead vapor temperature is not above the boiling point of the toluene-2-nitropropane azeotrope at the prevailing pressure, and conducting the distillation under these conditions until a residue is produced in which the ratio by weight of toluene to like-boiling nonaromatic hydrocarbons is at least 99:5.

13. The method of recovering toluene from a complex hydrocarbon mixture containing toluene and like-boiling paraffinic hydrocarbons, said mixture being substantially free from hydrocarbons normally boiling above 118° C., which comprises fractionally distilling said mixture in the presence of sufficient 2-nitropropane to vaporize and selectively remove as distillate substantially all of said like-boiling paraffinic hydrocarbons, thereby leaving behind a product enriched in toluene, the hydrocarbon content of said product being at least 95% toluene.

CHARLES R. CLARK.
